UNITED STATES PATENT OFFICE.

HARTLEY O. BAKER, OF PUEBLO, COLORADO, ASSIGNOR TO THE BAKER STEAM MOTOR CAR AND MANUFACTURING CO., INC., OF PUEBLO, COLORADO.

STEAM-CONDENSING APPARATUS.

1,375,272.

Specification of Letters Patent. Patented Apr. 19, 1921.

Application filed October 19, 1918. Serial No. 258,799.

To all whom it may concern:

Be it known that I, HARTLEY O. BAKER, a citizen of the United States, residing at Pueblo, in the county of Pueblo and State of Colorado, have invented certain new and useful Improvements in Steam-Condensing Apparatus; and I do hereby declare the following to be a full, clear, and exact description of the invention, such as will enable others skilled in the art to which it appertains to make and use the same.

This invention relates to new and useful steam condensing systems and the prime object of the invention is to provide one which possesses a maximum amount of condensing efficiency and which is so constructed and arranged that it will occupy a minimum amount of space.

Another object of the invention is to provide a steam condensing system, primarily designed for use in connection with motor vehicles and which embodies a plurality of condensing units arranged in circuit between the engine and the main water tank of the vehicle.

A further object of the invention is to employ steam condensing units of such construction as to produce a maximum amount of condensing efficiency.

A still further object of the invention is to provide the main radiator condenser with an overflow pipe leading into the smoke stack or chimney of the boiler, said overflow pipe being provided with a pressure relief valve which when open under back pressure accumulating in the system as when the vehicle is running under a load or in making sudden spurts, will allow the back pressure and any water or steam that may be present to escape into the top of the boiler chimney and thus assist in creating a draft through the water.

With these and other objects in view as will appear as the description proceeds, the invention comprises the various novel features of construction, combination and arrangement of parts as will be more fully described hereinafter and afterward specifically claimed.

Referring to the drawings:

Figure 1 represents a diagrammatic view of the steam condensing system;

Fig. 2 represents a side elevation of one of the auxiliary condensing units;

Fig. 3 represents a transverse sectional

view taken on a plane indicated by the line 3—3 of Fig. 2;

Fig. 4 represents a perspective view of the body portion of one of the condensing chambers of the condensing unit;

60

Figs. 5 and 5' represent perspective views of the head plates that are secured to the body portion of the condensing chamber;

Fig. 6 represents a sectional plan view through a modified form of condensing unit;

65

Fig. 7 represents a section, taken on a plane indicated by the line 7—7 on Fig. 6, looking in the direction of the arrow;

Fig. 8 represents a similar view, taken on a plane indicated by the line 8—8 of Fig. 70 6, looking in the direction of the arrow;

Fig. 9 is a perspective view of another form of condensing unit;

Fig. 10 represents a transverse sectional view through an auxiliary water tank or 75 another form of condensing unit on a plane indicated by the line 10—10 on Fig. 1;

Fig. 11 represents a longitudinal sectional view, taken on a plane indicated by the line 11—11 on Fig. 10;

80

Fig. 12 represents a rear elevation of the radiator or main condenser; and

Fig. 13 represents a vertical sectional view through the pressure relief valve, taken on a plane indicated by the line 13—13 of 85 Fig. 12.

Referring to the drawings and particularly to Fig. 1, E indicates a fluid expansion engine, such as are used in steam motor vehicle construction, B the boiler, R the radiator or main condenser, and A and A' auxiliary condensing units arranged in circuit between the engine and radiator condenser. The auxiliary condenser A is connected directly to the exhaust port of the engine by 95 a pipe 1 which gradually increases in diameter from the exhaust port toward the condenser A so that the fluid can freely exhaust from the engine while the vehicle is under a load strain such as climbing a hill 100 or as in sudden spurts and thus eliminate choking of the engine so well known and undesirable. 2 indicates a pipe leading from the opposite end of the condenser A to one end of the auxiliary condenser A', the latter 105 being connected by a pipe 3 to the top of the radiator or main condenser R, said connection being made through a plurality of branches 4 in order to more conveniently distribute the steam into the radiator so as 110

to produce the most efficient condensation. A pipe 5 leads from the bottom of the radiator R to an auxiliary water tank or another form of condensing unit W, the latter being relatively arranged with respect to the radiator so that the condensed fluid will flow by gravity back to this auxiliary water tank. 6 indicates the pipe connecting the auxiliary water tank or condenser to the main water tank T whereby the water as it accumulates in the auxiliary water tank may gravitate into the main tank in order to maintain a predetermined level within the auxiliary water tank.

15 The boiler B is provided with a chimney or smoke stack 7 into the upper end of which extends one end of an overflow pipe 8, the other end of the latter being connected to the upper part of the radiator condenser and at its connection with the radiator condenser is a pressure relief or check valve 9.

20 While I have shown two auxiliary condensers A and A' in the diagrammatic view of the invention, I desire to have it understood that this number may be either increased or decreased as desired and inasmuch as these auxiliary condensers are identical in construction it is believed that a description of one will suffice.

25 30 These auxiliary condensers A and A' are preferably constructed of the type of condensing unit shown in Fig. 2. This unit embodies a plurality of condensing chambers 10, 11, 12 and 13, each consecutively increasing in size for a purpose which will presently appear. Each of the condensing chambers is connected to the adjacent one by a plurality of pipes 14 to establish free and direct communication between said 35 chambers. 15 indicates the air pipes that are arranged transversely through each of the condensing chambers, said pipes in all of the chambers being of the same diameter in the present instance, but it is of course 40 to be understood that the diameters of the pipes in the various condensing chambers may be varied in direct ratio to the size of the chamber. The chamber 10 is provided with an inlet pipe 16 entering it from the 45 top while the chamber 13 is provided with an outlet pipe 17 extending from its lower portion so that any condensation that may accumulate within the various chambers can be freely exhausted from the condensing 50 unit under the pressure in the condensing system.

55 Inasmuch as the volume of the steam is greatest immediately upon leaving the engine and entering the condensing unit, the 60 first chamber 10 thereof is necessarily made the largest to take care of this. The steam decreased in volume by condensation will then pass on through the pipes 14 into the next smaller chamber 11 and like in the 65 chamber 10 will be partially condensed by

the air passing through the pipes 15 as it comes in contact with and passes around them. This action continues throughout the entire length of the condensing unit and by the time the steam reaches the end of the unit it will be partially condensed.

70 In Figs. 4 and 5 are illustrated the construction of each of the condensing chambers of the unit just described. The chamber comprises a body portion 18 through 75 which are transversely positioned the air pipes 15. The open ends of this body portion are closed by head plates 19 through which extends the terminal ends of the pipes 14, these head plates of course being hermetically sealed to the body portion so as to provide an air-tight chamber.

80 The modified form of condensing unit shown in Figs. 6, 7 and 8 comprises a tubular open-ended casing 20, preferably rectangular in cross section, one end of which is flared outwardly as at 21 to facilitate the entrance of the air. Arranged within the casing are a plurality of condensing chambers 22, 23, 24, 25, 26 and 27 which are 85 consecutively reduced in size for a purpose which will presently appear. These chambers are designed to be conveniently supported centrally within the tubular casing 20. Each chamber is provided with air 90 pipes 28 which extend therethrough, said pipes all being arranged in longitudinal alignment with each other and lengthwise of the casing 20 so that the air in entering the flared forward end of the casing 20 can 95 freely pass on through the various condensing chambers consecutively to absorb the heat of the steam as it enters and expands within the condensing chambers. It is to be noted that the air pipes 28 decrease in 100 diameter in each of the condensing chambers consecutively from the chamber 22 to the chamber 28 for the reason that as the steam passes on from one condensing chamber to the other expanding and losing its 105 heat, a less amount of air is necessary to condense the constantly decreasing volume of steam.

110 29 indicates an inlet pipe which extends transversely through the casing 20 and into 115 communication with the chamber 22 and may enter the latter at any convenient point. Each of the condensing chambers is connected to the adjacent one by a pipe 30. 31 indicates an outlet pipe leading from 120 the last chamber 27, the latter together with the pipes 30 being arranged in a plane substantially at the bottoms of the condensing chambers so that any condensation or water accumulated within the various chambers 125 can be freely forced through and expelled from the condensing unit. By positioning the condensing chambers centrally within the tubing it will be manifest that the air passing freely around these chambers to 130

gether with that passing through the chamber will effectually produce a maximum amount of condensing efficiency.

In Fig. 9 will be seen still another form of 5 condensing unit which comprises a pair of condensing chambers 32 of substantially the same size which are connected by a plurality of pipes 33, one of said chambers being provided with the inlet pipe 34 and the 10 other with an outlet pipe 35. Each of these chambers is provided with transversely extending air pipes 36. This unit functions in the same manner as the previously described ones and particularly that shown in Fig. 2.

15 In Figs. 10 and 11 are illustrated the construction of the auxiliary water tank or condenser and comprises a rectangular casing 37 entirely closed but provided longitudinally at one side of the top with a dome portion 38 which extends throughout the entire 20 length of the tank. 39 is a goose-neck overflow pipe connected centrally to the top of the dome portion 38 at the forward end of the tank. The pipe 5, Fig. 1, leads into the 25 front end of the tank at a point adjacent to its top and extends longitudinally of the tank to a point adjacent the rear thereof. A plurality of spaced serpentine coils 40 each have one end connected to the inlet pipe 5 30 while the other end extends upwardly and terminates in a downwardly curved end 41, said end terminating in substantially the same plane with the top of the tank for a purpose which will presently appear. The 35 tops of the serpentine coils are in a plane with that of the inlet pipe 5, and the tank is designed to contain a quantity of water sufficient to submerge these coils and the inlet pipe as indicated in Fig. 10. The pipe 6 connects the auxiliary water tank with the main 40 water tank T whereby water from the auxiliary tank may gravitate into the latter.

The radiator or main condenser R may be of any well known construction used in 45 steam motor car construction but in this instance is provided with the overflow pipe 8 at a point adjacent its top, said pipe being provided with a relief valve 9, the construction of which is more clearly indicated in 50 Fig. 13. This valve is spring pressed and is designed to open under a certain amount of back pressure say three pounds such as occurs when the car is climbing a hill or in sudden spurts. The opening of this valve 55 will relieve the back pressure and allow the same to escape into the chimney of the boiler which will materially assist in creating a draft therethrough. The radiator is also provided at its bottom with a drain cock 43. 60 From the foregoing description, it will be apparent that in the operation of the system, steam will flow from the engine through the auxiliary condensers A and A' to the radiator condenser R and from there the steam 65 in partially condensed or practically con-

densed form will pass on to the auxiliary water tank or condenser W and into the serpentine coils 40.

In the use of a system of this character and when the vehicle is climbing a hill, it 70 will be noted that the water in the auxiliary water tank W will flow toward the rear of the tank thus allowing any back pressure which may accumulate within the tank to escape through the goose-neck 39 to the atmosphere. On the other hand when the vehicle is going down hill the water will flow to the forward end of the tank thus closing and sealing the entrance to the overflow pipe 75 39 and the terminal ends of certain of the 80 pipes 40 but inasmuch as there is no back pressure in the system while the vehicle is going down hill, this rush of the water to the front of the tank will not affect the system in any way.

85 By the use of a steam condensing system of the above described construction, it will be apparent that the steam as it is exhausted from the engine will be thoroughly condensed and returned to the main water tank 90 without in any way choking the exhaust or affecting the operation of the engine.

While I have described the preferred embodiment of my invention I desire it to be understood that such changes in construction, operation and arrangement of parts 95 may be made when desired as are within the scope of the appended claims.

What I claim is:

1. A steam condensing system embodying 100 a water tank, condensing means, and a discharge pipe for the condensing means having a coil within the water tank below the water level and a discharge terminal above the water level directed toward the water.

105 2. A steam condensing system embodying a main water tank, an auxiliary water tank connected to the main water tank to supply the same, steam condensing means, a discharge pipe for the condensing means, coils 110 connected to said discharge pipe and located within the auxiliary water tank below the water level, said coils having discharge terminals extending upwardly out of the water and directed downwardly toward the water.

115 3. A steam condensing system embodying a main water tank, an auxiliary water tank connected to the main tank to supply water thereto, steam condensing means, a discharge pipe for the condensing means, the top of 120 the auxiliary water tank having a dome portion, coils connected to said discharge pipe and located within the auxiliary water tank below the water level, said coils having discharge terminals extending upwardly within 125 said dome portion and curved downwardly toward the water, and an overflow pipe connected to said dome portion and extending downwardly.

130 4. A steam condenser comprising an elong-

gated open ended casing for the passage of air therethrough, a series of condensing chambers within said casing for the flow of air around said chambers, pipes connecting 5 said chambers for the flow of steam from one chamber to the other, and pipes extending through the chambers for the flow of air therethrough and located between the first named pipes.

- 10 5. A steam condenser having an air passage, a series of steam condensing chambers in said passage, steam conducting pipes connecting said chambers for the flow of steam from one chamber to the other, and air pipes 15 extending through said chambers and arranged longitudinally of the air passage.
6. In a steam condensing system, a water tank, a boiler having a draft flue, steam con-

densing means, a discharge pipe for the condensing means leading to the water tank, 20 a pressure pipe for the discharge of steam from the condensing means connected to said flue for the discharge of steam into the flue to increase the draft, and a normally closed pressure valve for the pressure pipe 25 adapted to open and permit the flow of steam into the flue when the pressure rises above the predetermined amount.

In testimony whereof I have signed my name to this specification in the presence of 30 two subscribing witnesses.

HARTLEY O. BAKER.
